INVENTOR:
Paul F. Cox.

UNITED STATES PATENT OFFICE.

PAUL F. COX, OF BATTLE CREEK, MICHIGAN.

SOAP HOLDING OR RETAINING DEVICE.

No. 849,978.

Specification of Letters Patent.

Patented April 9, 1907.

Application filed January 22, 1907. Serial No. 353,521.

To all whom it may concern:

Be it known that I, PAUL F. Cox, of Battle Creek, in the county of Calhoun and State of Michigan, have invented certain new and useful Improvements in Soap Holding or Retaining Devices; and I hereby declare that the following is a full, clear, and exact description thereof, reference being had to the accompanying drawings, which form part of this specification.

This invention is an improvement in soap and soap holding or retaining devices of the kind in which the soap is provided with an interior member adapted to be engaged by a suspending or retaining device, by which the soap can be loosely but securely connected to a washstand, so that it can be easily and conveniently used by people, but cannot be surreptitiously removed.

The object of the present invention is to provide the soap with a tubular core-piece of flexible material and of novel construction affording means for the attachment of the suspending device, such core-piece being embedded in the soap during the molding process.

The invention will be clearly understood from the following description, in connection with the drawings, in which—

Figure 1 is a view of a cake of soap provided with my novel core and connected to a suspending device. Fig. 2 is an enlarged transverse section through the soap, showing the core enlarged. Fig. 3 is a view of one of the core-blanks before folding, and Fig. 4 is an enlarged view of the core removed from the soap. Fig. 5 is a section on line 5 5, Fig. 4. Fig. 6 is a sectional view of a cake of soap with a modified form of flexible core, and Fig. 7 is a view of the core shown in Fig. 6 separated from the soap.

The core is preferably made from a stout flexible fabric or material which can be readily wrapped around a mandrel or core and placed in a soap-mold, so as to be embedded in the soap, as shown in Figs. 2 and 6. The core is tubular and preferably slightly tapered or conical and may be provided with perforations in its sides, which will fill 45 with soap, and thus lock the core securely in place. The core is of a length equal to the greatest diameter of the soap.

The core 1 (shown in Figs. 1 and 2) may be made by cutting a blank of the form shown 50 in Fig. 3 from the material, such blank being

an approximately oblong rectangle, and is scored with four nearly-parallel lines *a b c d*, the space between the lines *a b* and *c d* forming the narrow sides of the core, and the space between the lines *b c* forming one wide side of the core, while the portions *1^a 2^a* outside the lines *a d*, respectively, are overlapped and form the opposite wide side of the complete core.

As shown in Figs. 6 and 7, the core can be 65 made by spirally twisting a strip of material 1^x into tubular form, the strip being preferably perforated before twisting or bending it into tubular form.

The cores are preferably provided with 70 holes *e* in their sides, as shown, so that the soap projecting into these holes will lock the core securely in place. The core is embedded in the soap when the latter is molded by placing the core upon a core-rod placed 75 within the mold while the soap is compressed therein. Preferably the core is made slightly tapered, smaller at top than at bottom, as shown, so that it will not easily or readily pull through the soap. Cores of this kind 80 will be light, inexpensive, and secure and will not injure the hands of users when the soap is nearly worn off the core.

Any suitable device can be used for suspending the soap in place for use. For example, it can be suspended from a chain 2 by means of a rod 3, having a head 3^a on one end and an eye 3^b on the other. Such rod can be inserted through the core, then fastened to a ring on the chain by means of a 85 lock 4, the hasp of which is run through the eye of the rod and through a ring or link of the chain, as shown in Fig. 1.

Having described my invention, what I claim as new, and desire to secure by Letters 95 Patent, is—

1. A cake of soap having a tubular core of flexible material embedded therein and extending therethrough, substantially as described.

2. A cake of soap having an internal tubular core embedded therein and extending therethrough, said core being larger at one end than at the other.

3. A cake of soap having a tubular core 105 embedded therein and extending therethrough, said core having holes or apertures in its walls for locking it to the soap.

4. A cake of soap having an internal tubular core of flexible material embedded there-

100

110

in and extending therethrough, said core being larger at one end than at the other, and having holes in its walls for locking it in the soap.

5 5. A cake of soap having an internal tubular core embedded therein and extending therethrough, said core being larger at one end than at the other; in combination with a suspending device passing through the core, substantially as and for the purpose described.

10 6. The combination of a cake of soap, a tubular tapered core provided with holes in its walls and extending through and embedded in said soap, and a suspending device engag-

ing the core, substantially as and for the purpose described.

15 7. The combination of a cake of soap, a tubular core of flexible material embedded in and passing through said cake, said core having holes in its walls; with a detachable rod passing through said core and suspending devices connected to the rod.

In testimony that I claim the foregoing as my own I affix my signature in presence of 25 two witnesses.

PAUL F. COX.
